CECIL R. HUBBARD AND HENRY R. GILSON, OF BADEN, PENNSYLVANIA, ASSIGNEES TO
NATIONAL METAL MOLDING COMPANY, OF PITTSBURGH, PENNSYLVANIA, A COR-
PORATION OF PENNSYLVANIA.

ELECTRICAL FITTING.

1,274,552.

Specification of Letters Patent.

Patented Aug. 6, 1918.

Application filed February 21, 1916. Serial No. 79,868.

To all whom it may concern:

Be it known that we, CECIL R. HUBBARD, residing at Baden, in the county of Beaver and State of Pennsylvania, a subject of the 5 King of Great Britain, and HENRY R. GILSON, residing at Baden, in the county of Beaver and State of Pennsylvania, a citizen of the United States, have invented or discovered certain new and useful Improvements 10 in Electrical Fittings, of which improvements the following is a specification.

Our invention relates to electrical fittings which include in their structure a pair of contactors arranged to receive lamps, extension 15 plugs, etc., and the object thereof is to provide a simply constructed and easily installed fitting having a plurality of pairs of contactors and adapted to be connected directly to supply conductors. A further and 20 more specific object of our invention is to provide a combination lamp socket and attachment plug characterized as just explained.

In the accompanying sheet of drawings, 25 forming part of our specification, we have illustrated the preferred embodiments of our invention. Figure 1 is a top plan view of the fitting connected to an electrical conductor conduit; Fig. 2 a bottom plan view of the 30 same fitting detached from the conduit; Fig. 3 a sectional view of the fitting and conduit taken on the line III—III, Fig. 1; Fig. 4 a sectional view taken on the line 35 IV—IV, Fig. 1; and Fig. 5 a view similar to Fig. 1 but showing a modification of construction. In Figs. 3 and 5 an attachment plug is shown with the fittings.

In the practice of our invention we provide a base block of insulation which is preferably 40 adapted to be attached to an electrical conductor conduit system. On this block there are mounted a pair of binding posts or equivalent members for the attachment of electrical conductors, and two or more pairs 45 of contactors, the contactors being electrically connected to the binding posts. To protect and properly insulate the contactors, a cover block of insulation, so formed as to receive and incase the contactors, is secured 50 to the base block.

In the illustrative embodiment of our invention, the base block 1 is a substantially flat block of porcelain provided on its bottom with a groove 2 to receive electrical

conductor conduits 3, to which the block 55 may be attached by screws 4 extending through the block and engaging a base plate 5 beneath the conduits. As seen in Figs. 2 and 4, the central portion of the base block is provided with two slots 6 and 6^a which 60 extend entirely through it and are separated by a bridge piece 7. Binding posts 8 and 8^a, preferably of the set-screw type, are attached one to each side of the bridge piece 7 and in such position that the binding 65 screws thereof lie one in each of the grooves 6 and 6^a. Although the connections are not shown herein, it will be understood that these binding posts are for the attachment of electrical conductors carried in the conduits 3, and the position of the binding posts is such that conductors, passing through the openings or slots in the base block from the bottom thereof, may be attached to the posts from the front of the base block. The attachment of the binding post 8 to the base 70 block is effected by two screws 9 and 9^a, and that of the post 8^a by a single screw 10, each of such screws extending through the bridge 7 from the lower side thereof. The contactors, which, in this embodiment of our invention, are attached to the base block and electrically connected to the binding posts, 75 are a pair of spring clips 11 and 11^a adapted to receive an attachment plug, and lamp 80 socket members consisting of a shell 12 and a base contact 13. The shell 12 is provided with lugs 24, which extend between the ends of the binding post 8 and the bridge 7 and are held in electrical contact with such binding post by the connecting screws 9 and 9^a, 85 while the base contact 13 is suitably mounted in the bridge 7 in position to be pressed into electrical contact with the post 8^a in the usual manner. As will be seen, the spring 95 clips 11 and 11^a are placed at one side of the shell 12, and, for economy of space and for operating efficiency, lie in a general plane oblique to the shell. These clips are attached to the block 1 by means of screws 14 100 and 14^a, which are of conducting material, and electrical continuity is established between such screws and the binding posts 8 and 8^a by means of short wires 15 and 15^a, 105 which lie in suitable recesses formed in the bottom of the bridge 7.

The cover block 16, which we provide for properly protecting and insulating the sev-

eral pairs of contactors, is preferably made of porcelain and is provided with a cylindrical bore 17 to receive the shell 12, and with recesses 18 and 18' to receive the clips 11 and 11'. Adjacent to the clips the cover has a flat face 21 against which an attachment plug 22 of standard form and construction may fit. The cover is attached to the base block by means of screws 19 in the manner indicated particularly in Fig. 4.

10 The fitting shown in Fig. 5 is the same as that shown in Figs. 1 and 4, inclusive, with the exception that the fitting of Fig. 5 is provided with a key switch 20, which may be 15 of any suitable form, the construction of which is well known and need not be herein explained in detail.

It will be observed of the fitting which we have provided that its construction and arrangement is such as to afford compactness in form, neatness in appearance, and efficiency in operation. After the various conducting and contacting members have been properly secured to the base block, the fitting comprises but two parts, the base block 25 and the cover block, which parts may be attached to or disconnected from each other without disturbing the conducting parts of the base. Furthermore, when making an 30 installation, the base block may be placed in position adjacent to the conduit 3, and the electrical conductors, extending from the conduits through the central openings or slots in such block, be attached to the binding posts from the front thereof. This is 35 made possible by reason of the fact that binding post screws are above the plane of the top of the base block as indicated in Fig. 4.

10 According to the provisions of the patent statute we have described the principle and operation of our invention together with the construction which we now consider to be the best embodiment thereof. However, we 45 desire to have it understood that the con-

struction shown and described is but illustrative, and that our invention may be practised in other forms of construction.

We claim as our invention:

1. A combination lamp socket and attachment plug comprising a base block of insulation provided with a pair of contactors adapted to be connected to an electrical circuit, a pair of lamp socket contact members including a shell secured to said block and electrically connected to said contactors, a pair of attachment-plug clips at one side of and lying in a general plane oblique to the longitudinal axis of said shell, said clips being electrically connected to said contactors, and a cover block of insulation secured to said base block, said cover block being provided with a cylindrical opening to receive said shell and with a recess to receive 55 said clips.

2. A combination lamp socket and attachment plug comprising a substantially flat base block of insulation provided near its center with a pair of slots and a bridge piece between them, a pair of binding posts for the attachment of electrical conductors mounted one on each side of said bridge piece, a lamp socket shell and base contact member mounted on the top of said bridge piece, a pair of attachment plug clips secured to said 70 block at one side of said shell, and a cover block of insulation secured to said base block, said cover block being provided with a cylindrical bore to receive said shell and with recesses to receive said clips.

In testimony whereof we have hereunto set our hands.

CECIL R. HUBBARD.
HENRY R. GILSON.
